THE NORRIS PETERS CO., PHOTO-LITHO., WASHINGTON, D. C.

UNITED STATES PATENT OFFICE.

EUGENE WOODLAND BURROUGHS, OF NORFOLK, VIRGINIA.

ELECTRIC-MOTOR WRENCH.

1,102,240.

Specification of Letters Patent.

Patented July 7, 1914.

Application filed March 9, 1914. Serial No. 823,451.

To all whom it may concern:

Be it known that I, EUGENE W. BURROUGHS, a citizen of the United States of America, and resident of Norfolk, county 5 of Norfolk, and State of Virginia, have invented certain new and useful Improvements in Electric-Motor Wrenches, of which the following is a specification.

This invention relates to certain new and 10 useful improvements in wrenches and it has for its objects among others to provide a simple, efficient and easily operated electrically actuated wrench. I apply modern up-to-date practice in motor work now being 15 used for drilling rails and for other purposes in the simplest form possible. I employ an electric motor designed to actuate a wrench through a train of gearing of sufficient reducing ratio to give the proper speed 20 to the wrench and the requisite power for turning the nut with a comparatively light and easily operated motor. The motor is placed upon a carriage of such form as to permit of ready adjustment of the wrench 25 to the rails without any needless leveling up or other time-consuming operations.

Other objects and advantages of the invention will hereinafter appear and the novel features thereof will be particularly 30 pointed out in the appended claims.

The invention is clearly illustrated in the accompanying drawings, which, with the numerals of reference marked thereon, form a part of this specification, and in which— 35 Figure 1 is a side elevation showing the application of my improved wrench to a rail, the latter, as well as a portion of the wrench proper, being shown in section. Fig. 2 is a top plan. Fig. 3 is a vertical cross 40 section on the line 3—3 of Fig. 1 looking in the direction of the arrows.

Like numerals of reference indicate like parts throughout the different views.

Referring to the drawings, 1—1 represent 45 supports which may or may not be tubular, each having one end bent to form a hook 2 designed to engage beneath the tread 3 and bear against the web 4 of a railway rail 5, the other ends of the supports 1—1 being 50 designed to rest upon the rail 6 to the nuts of the bolts of which it is desired to apply power to tighten up or loosen the nuts. Mounted upon the supports 1—1 is a carriage comprising preferably the three trans- 55 verse bars or supports 7, 8 and 9, the ends

of which are provided with the collars 10 to embrace the supports 1—1, see particularly Fig. 3, thus permitting of movement of the motor to and from the rail 6.

11 is an electric motor supported by and 60 suspended from said carriage.

12 and 13 are bearings carried by said motor in which is rotatably mounted the shaft 14 carrying the removable socket wrench 15 which, as seen in Fig. 1, is made 65 deep enough to allow for the travel of the nut 16 which it is designed to screw up or unscrew from the bolt 17 which holds the fishplates 18 in place. On the shaft 14 is a gear 19 with which meshes a smaller gear 70 20 on the shaft 21 of the motor. These gears are so proportioned as to be of sufficient reducing ratio to give the required speed to the wrench, as well as the requisite power for turning the nut. 75

22 is the feed cable connected with any suitable source of electricity for actuating the motor.

The supporting yokes 7 and 9 are provided with openings for the reception of the 80 guiding pins 23 carried by the motor near the front and rear to guide the motor in its vertical adjustments, which adjustments are accomplished by means of the setting wheel 24 engaging the threads 25 so that the motor 85 may be easily adjusted to the proper height to bring the socket wrench in alinement with the nut to be turned.

The carriage with its motor and accessories may be readily slipped off of the supports 1—1 and reversed so as to be used on the inside of the rail if the nuts are disposed upon the inside instead of upon the outside of the rail, as will be evident. The mode of use is apparent. The supports 1—1 are engaged with their hooks 2—2 over the one rail with the other ends of the supports resting upon the other rail and the socket wrench applied to the nut. As the current is turned on, rotary motion is imparted to 90 the shaft 14 and, consequently, to the socket wrench 15, through the medium of the gears 19 and 20 and the carriage and motor forced against the rail until the nut is screwed up or turned off, as may be desired. The motor 100 and wrench may be adjusted vertically in accordance with the position of the nut, by turning the setting wheel 24 in the proper direction. 105

Modifications in detail may be resorted to 110

without departing from the spirit of the invention or sacrificing any of its advantages.

What is claimed as new is:

- 5 1. In a motor-driven wrench, supports engageable with a rail, a carriage removably and adjustably mounted upon said supports in the direction of their length, an electric motor suspended from the carriage, a wrench and gearing actuated by the motor for turning the wrench.
- 10 2. In a motor-driven wrench, supports engageable with a rail, a carriage removably and adjustably mounted upon said support in the direction of their length, an electric motor suspended from the carriage, a wrench and gearing actuated by the motor for turning the wrench, and means for vertical adjustment of the motor.
- 15 3. In a motor-driven wrench, parallel supports having hooked ends to engage a rail, a carriage movably mounted upon said support in the direction of their length, a motor suspended from said carriage, a socket

wrench, its shaft, and reducing gearing between said shaft and the shaft of the motor.

4. In a motor-driven wrench, parallel supports having hooked ends to engage a rail, a carriage movably mounted upon said supports, a motor suspended from said carriage, a socket wrench, its shaft, reducing gearing between said shaft and the shaft of the motor, and means for bodily adjusting said motor vertically.

5. In a motor-driven wrench, parallel supports having hooked ends to engage a rail, a carriage movably mounted upon said supports, a motor suspended from said carriage, a socket wrench, its shaft, and reducing gearing between said shaft and the shaft of the motor, said carriage being reversibly mounted upon said supports.

Signed by me at Norfolk, Virginia, this third day of March 1914.

EUGENE WOODLAND BURROUGHS.
